UNITED STATES PATENT OFFICE.

JOHN ZUKOWSKI, OF DETROIT, MICHIGAN.

WIRE-CUTTING ATTACHMENT.

1,273,980.

Specification of Letters Patent. Patented July 30, 1918.

Application filed April 8, 1918. Serial No. 227,177.

To all whom it may concern:

Be it known that I, JOHN ZUKOWSKI, a citizen of Poland, residing at Detroit, county of Wayne, and State of Michigan, have invented certain new and useful Improvements in Wire-Cutting Attachments, of which the following is a specification.

This invention relates to improvements in implements of offense and particularly to bayonets as carried at the end of a rifle, which may be permanently engaged therewith so that the same may be advanced, and when engaged with wires or like entanglements, to sever the same in a rapid and efficient manner.

A further object is to provide such attachments in form which may be readily applied to bayonets of the ordinary type of construction and which may be operated by drawing a cord, thereby compressing springs which do the actual cutting.

These and other like objects are attained by the novel construction and combination of parts hereinafter described and shown in the accompanying drawing, forming a material part of this disclosure, and in which:

Figure 1 is a plan view of a gun having a bayonet thereon indicating the application of the invention.

Fig. 2 is an enlarged plan view of the bayonet, showing the attachment applied thereto.

Fig. 3 is a side elevational view of the same, and

Fig. 4 is an enlarged transverse sectional view taken on line 4—4 of Fig. 2.

In the drawings the numeral 10, represents the barrel of a conventional type of rifle, provided with the butt 11, and usual firing means 12.

The usual form of bayonet 14 is rigidly attached by clips 15 and 16 to the muzzle of the rifle, in an operative position, the manner of attachment being that of the ordinary type.

Fixed upon one of the edges, preferably the upper, of the bayonet 14, is a holder 18, in which is removably engaged a cutter blade 22, while immediately adjacent, and rearward thereof, is a second holder 23 carrying a removably engaged cutter blade 24, the holder being mounted to slide in a trackway 26, formed integrally with the rear of the bayonet in the shank 28, to which are secured the clips 15 and 16.

Fixedly mounted upon the extreme rear

of the bayonet shank 28, adjacent to the clip 16 are the inner ends of a plurality of arcuately bent flat springs 30, while their front ends are attached to an eye 31, engaged with the carrier or holder 23 in such manner that the latter element is normally projected to its full extent forward.

Also engaged to the eye 31, are link arms 32 having an open eye 33, at the extreme rear end, to which is attached a cord or chain 35, the same extending rearwardly along the barrel of the rifle to a point where it may be conveniently grasped by the operator.

In operation, the cord 35 having been drawn back to its full extent, the several springs 30 are bowed outwardly, while the slide knife 24, together with the holder 23, is retracted, leaving a considerable opening between the cutter blade 24 and the rear beveled edge of the fixed cutter 22, into which a wire or other article to be severed may be readily entered.

As a matter of fact, the advancement of the bayonet 14 into a fence or other entanglement causes the wire to drop into this opening formed between the cutters, so that upon suddenly releasing the cord 35, the springs 30 move violently outward, causing the cutters to come into intimate contact and sever whatever may be contained therebetween, and it is to be understood that the actual cutting action is due to the function of the springs 30, the same propelling the cutter blade 24 forward in a particularly easy and efficient manner.

Having thus described my invention what I claim as new and desire to secure by Letters Patent, is:

1. In a wire cutting attachment for bayonets, the combination with a fixed blade secured to the bayonet, a slide blade coöperative therewith, means for guiding said slide blade, means normally projecting said slide blade forward, and means for retracting said slide blade.

2. In a wire cutting attachment, the combination with a cutter blade rigidly engaged with the bayonet, a sliding blade coöperative therewith, means for guiding said sliding blade, a plurality of springs adapted to project said sliding blade forward, and means for retracting said sliding blade so as to present an opening between said cutter-blades for the entrance of the article to be cut.

3. In a wire cutter attachment for bayo-

nets, the combination with a beveled cutter holder rigidly engaged with a bayonet, a slide movable in alinement with said fixed holder, cutter blades removably engaged 5 with said slide and holder respectively, a plurality of springs secured at one end to the extremity of said bayonet and at the other to said slide, and means engaged with said slide whereby it may be brought rearwardly, said means extending to a point convenient of access.

4. In a wire cutting attachment, the com-

bination with a fixed cutter, a sliding cutter co-operative therewith, means for causing said sliding cutter to move in alinement with said fixed cutter, springs adapted to propel said sliding cutter forward, and a cord attached to said sliding cutter, said cord extending rearward to a point convenient of access and adapted to retract said sliding cutter, opposing the action of said springs. 15

In testimony whereof I have affixed my signature.

JOHN ZUKOWSKI.
